United States Patent Office

Des. 205,764
Patented Sept. 20, 1966

205,764

AMPHIBIOUS CAR

Roy W. Brisendine, 350 Main St., Marencie, Mich.

Filed Sept. 8, 1965, Ser. No. 86,898

Term of patent 14 years

(Cl. D14—3)

FIG. 1

FIG. 2

FIG. 3

FIG. 1 is a plan view of my new design.

FIG. 2 is a side elevational view thereof, and the other side of the car is identically opposite in appearance.

FIG. 3 is a bottom view thereof.

FIG. 4 is a front elevational view thereof.

FIG. 5 is a rear elevational view of the car.

The dominant features of my design reside in the portions shown in full lines.

I claim:

The ornamental design for an amphibious car, as shown and described.
